G. H. WHEARY.

TRUNK HINGE TRIMMING.

APPLICATION FILED FEB. 20, 1915.

1,180,269.

Patented Apr. 18, 1916.

UNITED STATES PATENT OFFICE.

GEORGE HENRY WHEARY, OF RACINE, WISCONSIN.

TRUNK HINGE-TRIMMING.

1,180,269.

Specification of Letters Patent. Patented Apr. 18, 1916.

Application filed February 20, 1915. Serial No. 9,566.

To all whom it may concern:

Be it known that I, GEORGE HENRY WHEARY, a citizen of the United States, and resident of Racine, in the county of Racine 5 and State of Wisconsin, have invented new and useful Improvements in Trunk Hinge-Trimming, of which the following is a description, reference being had to the accompanying drawings, which are a part of this 10 specification.

This invention relates to improvements in trunk hinge trimmings more particularly adapted for use with wardrobe trunks.

Many of the wardrobe trunks now on the 15 market rest upon one end and are divided vertically medially into two hinged together sections, the upper ends of which are open and provided with a hinged end top cover. In the particular trunk shown the top cover 20 is formed in two parts which are hinged together. These end covers have heretofore been secured to the sections by separate hinges and locking fixtures. As thus secured, the connections in many ways lack the 25 strength and rigidity desired in the manufacture of trunks.

It is one of the objects of the present invention to overcome the before mentioned objectionable features and combine the top 30 and side hinge portions with the adjacent trunk trimmings, and thereby provide a hinge trimming which possesses greater strength and rigidity than the same parts used independently.

35 A further object of the invention is to provide a trunk hinge fixture which is adapted to bind the adjacent sections and cover of a trunk of the before mentioned type in order to resist torsional strains or working 40 of the parts with relation to each other, and to bind the parts when in closed position, into a rigid structure.

45 A further object of the invention is to provide a trunk hinge trimming which is so constructed as to automatically lock the trunk sections together when the top cover is in closed position.

50 A further object of the invention is to provide a trunk hinge trimming which is of very simple construction, is well adapted for the purpose desired and which may be manufactured at a minimum cost.

With the above and other objects in view the invention consists of the improved trunk

hinge trimming and its parts and combinations as set forth in the claims, and all equivalents thereof.

In the accompanying drawing in which the same reference characters indicate the same parts in all of the views: Figure 1 is a 60 rear view of a wardrobe trunk provided with the improved hinge trimming, the trunk being indicated by dotted lines; Fig. 2 is an enlarged side view of the hinge trimming shown in open position, portions broken 65 away to show interior construction. Fig. 3 is a top view of the hinge trimming; and Fig. 4 is an edge view thereof.

Referring to the drawing the numeral 8 indicates the body section, 9 the wardrobe 70 section hinged thereto alongside its rear vertical edge and 10 the top cover which extends over the upper ends of both sections and is hinged to the body section of the trunk. The top cover 10 is divided medially 75 into two sections 11 and 12 on a line coincident with the line of division of the trunk sections and the improved hinged trimming 13 is adapted to connect the two covers and the two trunk sections together. 80 The trimming is in four parts and comprises the body section portion 14, the wardrobe section portion 15, the top cover inner section 16 and the top cover outer section 17, which are attached respectively to the body 85 section, the wardrobe section and the top cover inner and outer sections of said trunk. The fixture is stamped from sheet metal and when assembled is approximately of rectangular shape and is bent transversely medially of its length into L-shape to form the upper portion 18 and the side portion 19. While the transverse bend is of rounded 90 form as indicated by the numeral 20 to conform to the rounded edge portion of the 95 trunk, it is obvious that the corner may be formed with a right angle bend if desired.

The rectangle piece of material is divided medially, vertically and transversely to form the portions before described. The adjacent edge portions of the body and wardrobe sections of the trimming are provided with edgewise overlapping eyed portions 21 through which extends a hinge pintle member 22 to hingedly connect the two parts 100 together. The inner edges of the upper portions of the top cover sections 16 and 17 are also provided with edgewise overlapping

eyed portions 23 through which extends a hinge pintle member 24 to hingedly connect these parts together.

The side portion 19 of the trimming just above the eyed portions 21 is provided with a part circular outwardly embossed rib 25, the center of which is the point of junction of the four portions of the trimming. The rib is of semicircular form in cross section and the lower ends of the portions of rib formed on the top cover sections of the trimming are provided with downwardly projecting tongues 26 and 27 which enter the recesses 28 and 29 formed by the embossed rib portions of the body and wardrobe sections of the trimming. The opposite end portion of the rib of the inner top cover section 16 is also provided with a projecting tongue 30 which enters the recess 31 of the outer top cover section 17 when in closed position.

It will be noted that in view of the short radius or arc of swing of the projecting tongue 27, when only the front half of the top cover is swung to open position, that a portion of the rib forming the recess 29 is cut away on its outer side to form a side opening 29' to permit the movement of said tongue. All of the tongues are offset inwardly as indicated by the numeral 32 at their junction with the rib to form a flush outer surface when the parts are assembled, and the tongue 27 is provided with extension rib portion 25' to fill up the side opening 29' to preserve the ornate contour of the part circular rib.

The trimming is provided with perforations 33 to receive rivets or other securing means 34 for fastening the trimming to the trunk portions.

From the foregoing description it will be seen that the trunk trimming is of very simple construction and combines a plurality of hinges and locking fitting into one trimming.

What I claim as my invention is:

1. A trunk hinge trimming, comprising a four-part member having a locking engagement with each other, the parts being hingedly connected together in pairs.
2. A trunk hinge trimming, comprising a four-part member having a tongue and recess engagement with each other, the parts being hingedly connected together in pairs.
- 55 3. A trunk hinge trimming, comprising a

four-part member having a tongue and recess engagement with each other, the parts being hingedly connected together in pairs and one of the pairs having portions extending at an angle with relation to other portions.

4. A trunk hinge trimming, comprising a two top cover member hingedly connected together and having portions extending at right angles with relation to other portions, a body portion, and a wardrobe section portion hingedly connected to the body portion, all of said portions having an edge-wise tongue and recess locking engagement with each other.

5. A trunk hinge trimming, comprising an angular inner top cover member, an angular outer top cover member hingedly connected thereto, a body portion having an edge-wise engagement with the lower edge of the inner top cover member, and a wardrobe section member having an edge-wise engagement with the lower edge of the outer top cover member and having a hinged connection with the body portion, the adjacent portions of said members having a part circular rib embossed outwardly therefrom to form a tongue and recess engagement between the four members.

6. In combination with a trunk formed of two hinged together sections having open ends covered by a two part top cover which is hinged to one of the sections, a hinged trimming therefor comprising a two part hinged together cover member mounted on the two parts of the cover and hingedly connecting said cover parts together, said trimming parts having portions extending downwardly at right angles with relation to other parts, and a two part hinged together member mounted on both trunk sections and hingedly connecting said sections together, the two parts of the trimming mounted on the cover having a tongue and recess engagement with each other and also having a tongue and recess engagement with the two parts of the trimming mounted on the trunk sections.

In testimony whereof, I affix my signature, in presence of two witnesses.

GEORGE HENRY WHEARY.

Witnesses:

ANNA M. NELSON,
AL. A. RITTER.
